(57) **CLAIM**

We claim the ornamental design for a terminal collared electrode assembly for a medical probe, as shown and described.

DESCRIPTION

FIG. 1 is a perspective view of a terminal collared electrode assembly for a medical probe.

FIG. 2 is an enlarged perspective view of detail 2 circumscribed within FIG. 1.

FIG. 3 is a right side elevational view of the terminal collared electrode assembly for a medical probe of FIG. 2. FIG. 4 is a top plan view of the terminal collared electrode assembly for a medical probe of FIG. 2.

FIG. 5 is a left side elevational view of the terminal collared electrode assembly for a medical probe of FIG. 2.

assembly for a medical probe of FIG. 2.

FIG. 6 is a bottom plan view of the terminal collared electrode assembly for a medical probe of FIG. 2.

FIG. 7 is an enlarged front view of the terminal collared electrode assembly for a medical probe of FIG. 2; and, FIG. 8 is an enlarged rear view of the terminal collared electrode assembly for a medical probe of FIG. 2.

The parallel zig-zag dash lines in the drawings depict symbolic break lines. The break lines and the areas between the break lines form no part of the claimed design. The remaining broken lines illustrate portions of the terminal collared electrode assembly for a medical probe that form no part of the claimed design.

1 Claim, 4 Drawing Sheets
